STARTING POSITIONING MECHANISM

Daniel A. Armstrong and John C. Bandli, Minneapolis, Minn., assignors to Scott-Atwater Manufacturing Co. Inc., Minneapolis, Minn., a corporation of Minnesota

Application September 23, 1949, Serial No. 117,365

20 Claims. (Cl. 123—136)

1

This invention relates to an outboard motor and particularly to means for quickly placing certain parts of said motor in operative position.

It has been the universal custom heretofore upon starting an outboard motor to open a vent means for admitting air to the gasoline tank and to adjust a valve to open the fuel line to the carburetor or motor. After these actions are performed the spark adjusting lever is moved to starting position and the motor is cranked.

It is an object of this invention to provide means whereby when the motor is placed in starting position as when the spark adjusting lever is moved to starting position the vent passage in the gasoline tank will be opened and the fuel line from the gasoline tank to the motor will be opened as a result of placing said lever in starting position so that the operator does not have to open a vent passage or open a fuel control valve.

It is a further object of the invention to provide an outboard motor structure having a gasoline tank, a passage leading from said gasoline tank through which gasoline is conveyed to the motor, a vent passage for admitting air to said tank, a spark adjusting lever and automatically acting means for opening said passages to permit air to enter said gasoline tank and to permit gasoline to pass to said motor when said lever is placed in starting or running position.

It is another object of the invention to provide an outboard motor structure including a gasoline tank, a vent passage for admitting air to said tank, a passage leading from said tank for conducting fuel to said motor, a spark adjusting lever, and means operated by movement of said spark adjusting lever to stop position for closing said passages.

It is also an object of this invention to provide such a structure as set forth in the preceding paragraph, together with means for holding said spark adjusting lever in stop position, which latter means is preferably in the form of a readily engageable and disengageable latch.

It is more specifically an object of the invention to provide an outboard motor structure comprising a gasoline tank, a member secured to said tank and having a passage through which gasoline or fuel flows from said tank to said motor, said member having a second passage forming a vent passage through which air can enter said tank, a member preferably in the form of a plunger movable in said first mentioned member and having means carried thereby for closing and opening said passages, a spark adjusting lever, said member being moved in one direction by a

spring for opening said passages and being movable in the opposite direction by a member carried by said spark adjusting lever for closing said passages.

5 These and other objects and advantages of the invention will be fully set forth in the following description made in connection with the accompanying drawings in which like reference characters refer to similar parts throughout the several views and in which:

10 Fig. 1 is a plan view showing certain parts of an outboard motor including the spark adjusting lever, some parts being broken away and other parts being shown in horizontal section;

15 Fig. 2 is a view partly in side elevation and partly in vertical section of a portion of a gasoline tank and parts carried thereby;

Fig. 3 is a partial view similar to Fig. 2 showing some parts in different positions;

20 Fig. 4 is a view similar to Fig. 1 showing some of the parts in different positions;

Fig. 5 is a view partly in vertical section and partly in side elevation showing a spark adjusting lever and a latch carried thereby; and

25 Fig. 6 is a bottom plan view of the device shown in Fig. 5.

Referring to the drawings, certain parts of an outboard motor are shown comprising the gasoline tank 10, the fly wheel 11, the drive shaft 12 which has secured thereon at its upper end a nut 13 under which is disposed a washer 14. A spark adjusting lever 15 is shown having a handle 15a, which lever is oscillatable about the center of shaft 12.

30 35 In accordance with the present invention a member 20 is provided, the same having a flange 20a which fits against and is secured to the bottom plate 10a of the gasoline tank 10. Plate 10a has a raised portion or boss 10b having an aperture or opening 10c therethrough having a counterbore 10d. Member 20 has a cylindrical portion or flange 20b which fits in counterbore 10d. A screen or filter not shown will preferably be carried in member 20 within the flange 20b.

40 45 Member 20 has a chamber 20c below opening 10c from which leads a passage or conduit 20d. Passage 20d is surrounded by a valve seat 20e and a passage 20f leads from valve seat 20e to and through one end of member 20. Member 20 has a downwardly extending hub or boss 20g in which a passage 20h is formed which communicates with passage 20f. Member 20 has another downwardly extending hub or portion 20i which is provided with a passage 20j extending centrally therethrough and which communicates with pas-

2

sage 20f. Passage 20h is interiorly threaded for the attachment of a coupling and conduit to convey gasoline to the carburetor 23. The portion 20i is threaded at its lower end for the attachment of any desired coupling. Passage 20j communicates with the atmosphere. A passage 20k leads upwardly from passage 20f and communicates at its upper end with a tube or conduit 21 which extends across tank 10 and has its upper end in engagement with a cap 22 having a cylindrical body extending through an opening in the top plate 10b of tank 10 and having a flange 22a engaging the inner side of plate 10b to which it will be connected in any suitable manner, as by soldering or welding. Member 22 has a cylindrical chamber therein from which extends a conical chamber 22b. The upper end of tube 21 is closed and while this might be done in any suitable manner, in practice it has been done by dipping said end in solder. The upper end of tube 21 is in substantial engagement with the wall of chamber 22b, said tube being secured in any suitable manner in bottom plate 10a. Tube 21 is provided with a plurality of circumferentially spaced holes 21a which open into the cylindrical chamber within member 22. A member 24 in the form of a cylindrical plunger is disposed in passage 20f, the same having thereon adjacent one end a valve 24a which cooperates with valve seat 20e. A circular packing ring 25 is carried in an annular groove in plunger 24 spaced from valve 24a. Said ring 25 closely engages the wall of passage 20f. Another annular packing ring 26 is carried by plunger 24 some distance from ring 25, said plunger being somewhat reduced in diameter between said rings. Plunger 24 has an enlarged portion fitting an enlarged portion of passage 20f and a conical valve portion 24b is formed on plunger 24 cooperating with a frusto-conical seat 20m in passage 20f. Another annular packing ring 27 is carried in a groove in plunger 24 spaced some distance from portion 24b so that portion 24b is between rings 26 and 27. It will be seen that when member 24 is in the position shown in Fig. 2 that passage 20d is closed and that passages 20j and 20k are closed so that there is no communication therebetween. When the member 24 is in the position shown in Fig. 3, it will be seen that passage 20d is open and gasoline or fuel can thus pass through passage 20d and into passage 20h. Also, as shown in Fig. 3, passages 20k and 20j are in communication through passage 20f. Plunger 24 fits in and is guided in a bore in a bracket 28 secured by suitable screws 32 to a portion of the motor frame. As shown in Fig. 1, bracket 28 is of angular form. Plunger 24 has thereon a washer or collar 29 bearing against a pin 30 and a compression coiled spring 31 surrounds plunger 24, the same bearing at one end against washer 29 and at its other end against one end of member 20.

The spark adjusting lever 15 has secured to its underside a plate-like member 33, which member may be secured in any suitable manner, as by screws or bolts 34 and 35. Member 33 is provided with an arcuate slot 33a through which screw 35 passes and member 33 is oscillatable about screw 34 for the purposes of properly positioning the same. Member 33 has a downwardly extending portion at one end to which is secured a resilient plate 36. Plate 36 can be secured in any suitable manner, as by the rivets 37. Plate 36 is positioned so that in the oscillation of lever 15 it will in the desired position engage the end of plunger 24, as shown in Fig. 2.

A pin 38 projects from the bottom of gasoline tank 10 and is adapted to be engaged by the hook portion 39a of a latch lever 39 which is pivotally secured to spark adjusting lever 15 by a headed screw 40 which overlies a washer 44. A torsion wire spring 41 surrounds screw 40 and has one end engaging lever 15 and its other end engaging latch 39, said spring tending to swing latch 39 in a counterclockwise direction, as seen in Fig. 6. 5 Latch 39 has an arm extending approximately longitudinally of lever 15 which is provided with a laterally extending projection 39b which has a downwardly turned end. Said arm portion of latch 39 extends under a plate 42 disposed in a recess 15b formed in lever 15, which plate is secured by a headed screw 43 to the handle portion 15a of lever 15. A portion 46 of the hood which surrounds the gasoline tank and upper portion of the motor is shown.

10 In operation when the motor is in stop position the plunger 24 will occupy the position shown in Fig. 2. At this time the spark adjusting lever 15 has been swung clockwise to its extreme or stop position, as shown in Fig. 1, and latch 39 is engaged with pin 38. As is well known in the art, 15 when the spark lever is swung to stop position a portion of the magneto is moved to retard the spark to a point at which the motor cannot be started. The latch and pin are provided to prevent lever 15 being moved by someone contacting it or brushing against it. The member 36 has pushed plunger 24 to its inward position and the portion 24a thereof is now engaged with seat 20e so that passage 20h is closed. No fuel can now 20 pass from chamber 20c into passage 20b and to the carburetor. With lever 15 in stop position therefore the motor cannot be started. The ring 26 as well as portion 24b close passage 20f so that 25 communication between passages 20k and 20j is 30 engaged with pin 38. As is well known in the art, when the spark lever is swung to stop position a portion of the magneto is moved to retard the spark to a point at which the motor cannot be started. The latch and pin are provided to prevent lever 15 being moved by someone contacting it or brushing against it. The member 36 has pushed plunger 24 to its inward position and the portion 24a thereof is now engaged with seat 20e so that passage 20h is closed. No fuel can now 35 pass from chamber 20c into passage 20b and to the carburetor. With lever 15 in stop position therefore the motor cannot be started. The ring 26 as well as portion 24b close passage 20f so that 40 communication between passages 20k and 20j is cut off. It is not necessary that the tapered portion 24b engage the tapered portion 20m as the ring 26 will prevent communication between passages 20k and 20j. The vent opening to the tank 10 through tube 21 is thus closed. Spring 31 is 45 at this time compressed. As soon as spark adjusting lever 15 is moved in a counter-clockwise direction, as when it is moved to starting position, spring 31 will expand and move plunger 24 to the position shown in Fig. 3. At this time passage 20d is open and fuel can pass from chamber 20c through passage 20d into passage 20h and thence to the carburetor 23. Also air can pass into passage 20j and through passage 20f and passage 20k to the tube 21 so that it can enter 50 the tank 10 through the holes 21a. The fuel line and the vent passage for the gasoline tank are thus automatically opened by the spring 31 and the attention of the operator is not necessary for such opening. When spark lever 15 therefore is 55 in starting position the fuel and vent lines are open and the spark is advanced to a point where the motor can be started. The number of operations which the operator must make are thus reduced. It is more or less a common thing for the operator to forget to open the vent passage or the fuel valve and this results in starting or running trouble. With the present structure the 60 number of operations or things to do upon starting are considerably reduced. The operator need only move the spark adjusting lever and then crank the motor. The latch 39 can be readily disengaged by the operator pressing with his thumb on the portion 39b of latch 39. This can be easily done as he is grasping handle 15a with 65 one hand and can use the thumb of said hand.

When lever 45 is moved to stop position, latch 39 automatically engages pin 38.

From the above description it will be seen that we have invented a simple, efficient and highly useful structure for an outboard motor. The invention, as stated, materially reduces the number of things which the operator must do upon starting and stopping the motor. When he swings the spark adjusting lever to start position the vent passage to the tank and the valve controlling the fuel line are automatically opened and when he moves the spark adjusting lever to stop position he simultaneously closes the fuel control valve and closes the air vent to the gasoline tank. The invention has been amply demonstrated in actual practice, found to be very successful and efficient and will soon be in commercial production.

It will of course be understood that various changes may be made in the form, details, arrangement and proportions of the parts, without departing from the scope of applicants' invention, which generally stated, consists in a device capable of carrying out the objects above set forth, in the parts and combinations of parts disclosed and defined in the appended claims.

What is claimed is:

1. An outboard motor structure having in combination, a gasoline tank, a vent passage for admitting air to said tank, a conduit for conducting gasoline from said tank to said motor, and a member outside of said tank for substantially simultaneously opening said vent passage and opening said conduit to permit discharge of gasoline from said tank.

2. An outboard motor structure having in combination, a gasoline tank, a vent passage for admitting air to said tank, a second passage for conducting gasoline from said tank to said motor, a spark adjusting lever movable to starting and stop positions, and means actuated upon movement of said spark adjusting lever to starting position for opening said vent passage and opening said second passage to permit discharge of gasoline from said tank to said motor.

3. An outboard motor structure having in combination, a gasoline tank, a vent passage for admitting air to said tank, a second passage for conducting gasoline from said tank to said motor, a spark adjusting lever, and means operated upon movement of said lever to stop position for closing both of said passages.

4. The structure set forth in claim 3, and means for holding said spark adjusting lever in stop position.

5. An outboard motor structure having in combination, a gasoline tank, a passage for conducting gasoline from said tank to said motor, a valve for opening and closing said passage, a spark adjusting lever movable to stop and starting positions, and automatically acting means for moving said valve to open said passage when said lever is moved to starting position.

6. The structure set forth in claim 5, a vent passage for admitting air to said tank, said last mentioned means acting to open said passage when said lever is moved to starting position.

7. An outboard motor structure having in combination, a gasoline tank, a passage for conducting gasoline from said tank to said motor, a valve for opening and closing said passage, a spark adjusting lever movable to stop and starting positions, and means for moving said valve to close said passage when said lever is moved to stop position.

8. The structure set forth in claim 7, a vent passage for admitting air to said tank, and means for closing said vent passage when said lever is moved to stop position.

9. An outboard motor structure having in combination, a gasoline tank, a vent passage for admitting air to said tank, a spark adjusting lever movable to stop and starting positions, and means for opening said vent passage when said lever is moved to starting position.

10. An outboard motor structure having in combination, a gasoline tank, a vent passage for admitting air to said tank, a spark adjusting lever movable to stop and starting positions, and means for closing said vent passage when said lever is moved to stop position.

11. An outboard motor structure having in combination, a gasoline tank, a vent passage for admitting air to said tank, a conduit for conducting gasoline from said tank to said motor, a valve for controlling said conduit, a member for moving said valve, means carried by said member for closing said vent passage, a spark adjusting lever movable to stop and starting positions, and means carried by said spark adjusting lever for moving said member to close said valve and close said vent passage when said lever is moved to stop position.

12. An outboard motor structure having in combination, a gasoline tank, a vent passage for admitting air to said tank, a conduit for conducting gasoline from said tank to said motor, a valve for controlling said conduit, a member for moving said valve, means carried by said member for closing said vent passage, a spark adjusting lever movable to stop and starting positions, and means for moving said member to open said valve and open said vent passage when said spark adjusting lever is moved to starting position.

13. An outboard motor structure having in combination, a gasoline tank, a member secured to said tank and having therein a passage for gasoline to pass from said tank, a valve seat about said passage, a valve cooperating with said seat, said member having a second passage for air to enter said tank, a plunger movable in said member, a compression coiled spring disposed about said plunger, a valve carried by said plunger cooperating with said valve seat, and means carried by said plunger for closing said second passage whereby said spring acting on said plunger keeps said passages in open position.

14. The structure set forth in claim 13, and means for moving said plunger to close said valve and close said second passage when said motor is in stop position.

15. The structure set forth in claim 13, and means for moving said plunger to open said valve and to open said second passage when said motor is placed in starting position.

16. The structure set forth in claim 13, a spark adjusting means movable to stop and starting positions, and means on said lever for engaging said plunger to close said valve and close said passage when said lever is moved to stop position.

17. The structure set forth in claim 13, a spark adjusting means movable to stop and starting positions, and a spring for moving said plunger to open said valve and to open said passage when said spark adjusting means is moved to starting position.

18. An outboard motor structure having in combination, a gasoline tank, a venting means for said tank for permitting the entry of air

thereto, a conduit for conducting gasoline from said tank, a control means for said conduit manually movable to positions for starting and stopping said motor, and a member outside of said tank for simultaneously operating said venting means to vent said tank and operating said control means to permit the discharge of gasoline from said tank when said control means is moved to position for starting said motor.

19. An outboard motor structure having in combination, a gasoline tank, a vent passage for admitting air to said tank, a second passage for conducting gasoline from said tank, a control means for said second passage, and a member outside of said tank manually movable to a position to stop said motor and close both of said passages.

20. An outboard motor structure having in combination, a gasoline tank, a vent passage for

admitting air to said tank, a second passage leading from said tank to supply fuel to said motor, means for closing said vent passage, means for closing said second passage, and a movable member outside of said tank movable to positions to stop said motor and for actuating both of said means for closing both of said passages.
